Inventor: Charles A. Gibford,
By Thomas G. Orrig, Atty.

UNITED STATES PATENT OFFICE.

CHARLES A. GIBFORD, OF NEWTON, IOWA.

FOLDING FLOWER-STAND.

SPECIFICATION forming part of Letters Patent No. 450,146, dated April 14, 1891.

Application filed October 24, 1890. Serial No. 369,248. (No model.)

To all whom it may concern:

Be it known that I, CHARLES A. GIBFORD, a citizen of the United States of America, and a resident of Newton, in the county of Jasper 5 and State of Iowa, have invented a Folding Flower-Stand, of which the following is a specification.

The object of my invention is to provide a convenient and useful flower-stand having 10 arms adapted to support flower-pots, which arms project radially from an upright support and are adapted to be folded against the central support to occupy a less space in transportation or storage.

15 My invention consists in the construction of a flower-stand composed of a suitable support having arms radiating therefrom, which arms are hinged to the said support and provided with braces also hinged to said support, which braces have a sliding connection with the radiating-arms.

20 Referring to the accompanying drawings, Figure 1 is a top view, and Fig. 2 a central sectional view, of my complete device. Fig. 25 3 is a detail view showing that portion of my device to which the radial arms are hinged.

In Fig. 2, A represents a metal tube fixed in the center of a base-block B, and supported by means of said base-block in a vertical position.

30 C represents a cylindrical wooden block, having a vertical bore in its center corresponding in size with the tube A. The block C is loosely mounted upon the tube A just 35 below the middle of said tube, and a collar D is adjustably fixed on said tube above and below said block C to prevent said block from sliding up or down on said tube.

F represents a metal collar fixed about the 40 circumference of the block C. This collar F projects above the top of the block C, and is provided with notches in its upper edge.

H represents an annular ring fixed to the top of the block C by means of common staples H².

45 J represents one of the pot-supporting arms, made of a single piece of wire, one end of which wire is secured to the ring H by means of an eye formed on said wire. The outer 50 projecting portion of said wire is bent to form a loop adapted to engage and support a flower-pot. The hitherto free end portion of the

wire is then returned to a point near the collar F, and secured to the wire secured to ring H by means of a clip J², which is bent about 55 the two portions of wire and soldered thereto.

K represents a wire brace, the lower end of which is fixed to a pivoting device, which latter is identical in form and mode of operation with the device described in connection 60 with the arms J. This brace K has an elongated loop L, formed integral with its outer end, adapted to admit the shank of the arm J and slide thereon.

M represents a cup-shaped device fixed to 65 the upper end of the tube A for ornamental purposes.

The lower rotating frame only has been described, the upper one being identical therewith, except as to size, in which respect they 70 differ in that the lower frame is preferably the larger. Any number of rotating frames may be mounted on the upright support.

When the complete device is in position to receive plant-containing vessels, the arms J 75 radiate from the central support in a horizontal direction, that portion of each arm adjacent to the point of attachment resting in one of the notches in the annular collar F, by means of which notches the arms J are so 80 held that their outer end portions are equally separated and prevented from coming in contact with each other. The outer end portions of the arms J are supported by means of the braces K, which braces project upward and 85 outward from the central support and have a sliding connection with the shank of the arms J.

When it is desired to pack the stand for 90 shipment, the arms J may be folded upward against the central support A, and in so doing will take the outer end of the braces K with them, and a cord bound about the folded arms and support A will confine the complete device in a compact form, so that it will occupy a much less space than when open.

By means of the adjustable collars D the 95 pivotal device may be readily raised or lowered to suit the varying heights of plants.

By placing saucers or trays in the loops at 100 the outer ends of the arms J my device may be advantageously used to display vegetables or fruit thereon.

I claim as my invention—

1. A flower-stand consisting of a central support having arms hinged thereto and radiating therefrom, and braces hinged to the central support, said braces having a sliding connection with the said arms, as and for the purposes stated.

2. In a flower-stand, a block mounted upon a central support and adapted to rotate about said central support, a notched rim secured to said block, arms pivoted within the block adapted to rest within the notches of the rim, said arms being capable of vertical movement, and braces to support the said arms hinged at one end to the central support and their other ends adapted to travel upon the said arms when the latter are moved vertically.

3. In a flower-stand, a central vertical support mounted upon a suitable base, a plurality of blocks adjustably mounted upon and adapted to rotate about said support, notched rims fixed to the circumference of the blocks, arms and braces hinged within the blocks, said arms radiating from the central support adapted to receive and hold containing-vessels, the outer ends of said arms being supported by means of a sliding connection with the outer ends of the hinged braces, as shown and described, to operate in the manner set forth, for the purposes stated. 30

CHARLES A. GIBFORD.
